E. I. LA CHAPELLE

SHOE BOTTOM

Filed July 19, 1927

UNITED STATES PATENT OFFICE.

EUCLID I. LA CHAPELLE, OF BROCKTON, MASSACHUSETTS.

SHOE BOTTOM.

Application filed July 19, 1927. Serial No. 206,886.

The term "shoe" occurring in the specification and in the claims is to be interpreted to include the term "boot".

My invention relates to shoes such as of the well known Goodyear welt and McKay types and more particularly to the inner bottoms thereof.

In the manufacture of a shoe of this character the inner plane face of the insole is forced lower than its peripheral margin portion and this defective condition is aggravated under the effect of wear and is especially objectionable at the forepart as then the peripheral margin portion of the insole irritates the foot from undue contact therewith.

Experiments have demonstrated that the forepart inner bottom of a welt shoe could be improved by providing a felt insole and a sock-lining preferably of sheep-skin and permanently attached to the insole and preferably of a dimension extending within a substantial distance of the peripheral margin of the insole and preferably also a forepart filler, preferably of firm felt, and of a dimension extending within a substantial distance of the peripheral margin of the insole and adapted to be applied underneath the sock-lining to thereby bring about in conjunction with the sock-lining a protuberance at the inner plane face of the shoe bottom forepart preferably projecting slightly above the peripheral margin portion of the insole.

In view of eliminating in a shoe of the character described the objections noted and in view also of relieving the foot in a better manner than heretofore from undue contact with the peripheral margin portion of the insole, my present invention has for objective the provision in the bottom of a shoe of the character described of a felt insole and of a sock-lining preferably of sheep-skin permanently attached to the insole; and of a forepart filler, invariably of a dimension extending within a substantial distance of the peripheral margin of the insole and adapted to be applied between the insole and the sock-lining to form, in conjunction with the sock-lining, a protuberance projecting above the peripheral margin portion of the insole.

As shown in the drawings:

Fig. 1, is a plan view of a welt shoe felt insole. 55

Fig. 2, is a plan view of a sheep-skin leather sock-lining.

Fig. 3, is a sectional view taken on line 3—3 Fig. 2. 60

Fig. 4, is a plan view of the welt shoe felt insole and of the calf-skin leather sock-lining permanently attached thereto and showing also a felt forepart filler in dotted lines. 65

Fig. 5, is a plan view of the felt forepart filler. 65

Fig. 6 is a cross-section through the forepart of a welt shoe of the well known Goodyear type incorporating my invention.

Referring further to the drawings:

1, shows a welt shoe felt insole, which is, 70 preferably, of about three sixteenths of an inch thick and which is made, preferably also in accordance with the well known Gem process—felt insole and reinforcing canvas cemented together. The sock-lining 2, is, 75 preferably, of sheep-skin and is skived at its peripheral margin as shown at 3, and as still more clearly shown in Fig. 3. I, preferably, attach the sock-lining to the insole by the stitches 4, at the skived edge 80 portion 3. Thereafter I make an incision 5, shown in Fig. 4, through the sock-lining back of the ball line portion of the insole and I insert between the insole and the sock-lining the forepart filler 6, shown in Fig. 5, 85 which is about one sixteenth of an inch thick, shown by dotted lines 7, Fig. 4. As shown by dotted line in Fig. 5, the forepart felt filler 6, is skived at 8 (Figs. 5 and 6) around its peripheral margin; and as shown in Fig. 6, the inner plane face of the shoe bottom within a substantial distance of the peripheral margin of the insole is advisedly on a higher plane than the peripheral margin 90 portion of the insole. 95

It is within the spirit of my invention to permanently unite by stitches or otherwise the forepart filler to the insole and then apply the sock-lining to the felt insole and permanently attach the same thereto. 100

A very thick sock-lining of a dimension extending within a substantial distance of the peripheral margin of the insole forepart and permanently attach to the felt insole

may, by itself, provide for a proper protuberance as aimed at by my present invention. The appended claims, whenever the context so permits, are to be interpreted 5 in that sense to give effect to my invention and this patent.

Having thus explained the nature of my invention and shown the same in the best form now known to me, what I claim as 10 new and desire to secure by Letters Patent of the United States is:

1. In the bottom of a shoe of the character described, a felt insole, a sock-lining permanently attached to the felt insole and a forepart felt filler having its margin extending within a substantial distance of the peripheral margin of the felt insole and applied between the felt insole and the sock-lining to form, in conjunction with the sock-lining, a protuberance projecting above the peripheral margin portion of the felt insole. 15

2. In the bottom of a shoe of the character described, a felt insole, a sock-lining permanently attached to the felt insole and a forepart filler having its margin extending within a substantial distance of the peripheral margin of the felt insole and applied between 20

the felt insole and the sock-lining to form, in conjunction with the sock-lining, a protuberance projecting above the peripheral 30 margin portion of the felt insole.

3. In the bottom of a shoe of the character described, a felt insole, a sock-lining permanently attached to the forepart of the felt insole and a protuberance at the inner plane 35 face of the forepart of the felt insole extending within a substantial distance of the peripheral margin of the felt insole and projecting above the peripheral margin portion of the felt insole. 40

4. In the bottom of a shoe of the character described, a felt insole, a sock-lining having its margin extending within a substantial distance of the peripheral margin of the felt insole and permanently attached to the felt 45 insole and a protuberance at the inner plane face of the forepart of the felt insole extending within a substantial distance of the peripheral margin of the felt insole and projecting above the peripheral margin portion 50 of the felt insole.

In testimony whereof I have signed my name to this specification.

EUCLID I. LA CHAPELLE.
